PREFABRICATED PARTITION

Howard W. Barss, Jr., Framingham, Mass., assignor to Power Engineering Co., Framingham, Mass., a corporation of Massachusetts

Filed Nov. 18, 1960, Ser. No. 70,285

2 Claims. (Cl. 189—34)

This invention relates to partitions for use in the interiors of buildings, and particularly to partitions of the prefabricated type.

The type of partition for which this invention is particularly adapted consists of a framework made up of channel types of adjustable framing bolted together, and panels secured in the framing. The channels which make up the framing, and the panels, may be furnished cut to the desired sizes and assembled on the job.

The general object of this invention is to provide a partition framework which is adaptable for use with panels of various thicknesses as well as sizes, which requires no welding, which may be dismantled and used in a different location and which, in the completed assembly, provides a flush dust-free surface on both sides of the partition.

The framework is made up of channels with inturned lips bolted back to back with short channel-shaped spacers disposed between at intervals. The panels are secured to the framework by retainer strips having spring flanges which engage the lips of the channels, and side flanges, which overlie the panels.

In the drawings illustrating the invention:

FIG. 1 is a front elevation, partly broken away, of a partition constructed according to the invention;

FIG. 2 is an enlarged fragmentary cross-section taken along line 2—2 of FIG. 1;

FIG. 3 is an enlarged fragmentary cross-section taken along line 3—3 of FIG. 1;

FIG. 4 is an enlarged perspective view of one of the intermediate spacers;

FIG. 5 is an enlarged perspective view of a junction spacer; and

FIG. 6 is an enlarged perspective view of a corner spacer.

A typical complete partition, as shown in FIG. 1, consists of top and bottom rail assemblies 10 and 11, end rail assemblies 12 and 13, a number of intermediate column assemblies 14, and panels 15.

A typical column assembly, as shown in FIG. 2, is made up of two channels 16 and 17 placed back to back, a number of spacers 18 secured between the channels by bolts 19 and nuts 20, and a pair of retainer strips 21 and 22. The channels have inturned lips 16a and 17a, respectively. The retainer strips have spring flanges 21a, 22a which engage inside lips 16a, 17a, respectively. These flanges terminate in ribs 21b, 22b which engage the inner edges of the lips. The flanges have sufficient resiliency so that strips 21, 22 can be snapped on and off the channels. The strips also have side flanges 21c, 21d which extend sideward beyond the channels and hold the panels 15 in place.

The intermediate spacers 18 consist of short sections of open-faced channel, and have elongated holes 23. The channels 16 and 17 are provided with holes at spaced intervals so that the spacers may be bolted in at various locations. The elongated holes in the spacers permit some adjustment of their position in the longitudinal direction of the channels.

The bottom rail assembly, as shown in FIG. 3, is formed of a pair of channels 24 and 25 placed back to back, and a pair of retainer strips 26 and 27. The channels 24 and 25 are similar in all respects to channels 16 and 17 and have inturned lips 24a and 25a. The strips 26 and 27 have spring flanges 26a and 27a and ribs 26b, 27b,

2

similar to flanges 21a and 22a, and ribs 21b, 22b, which engage lips 24a and 25a, respectively. Strips 26 and 27, however, have extending upper flanges 26c, 27c, similar to flanges 21c, 22c, but are cut off flush with channels 24 and 25 at the bottom. Channels 24 and 25 are bolted to the floor 28 at intervals by bolts 29.

The top rail assembly is similar to the bottom rail assembly except that the retainer strips are flush with the channels at the top and have downwardly extending flanges which overlap the panel 15.

The top and bottom rail assemblies may have spacers 18 disposed between the channels. However, if the distance between column assemblies is not too great, the junction spacers 30 and corner spacers 31, shown in FIGS. 5 and 6, are sufficient to hold the top and bottom pairs of channels in the right position.

A junction spacer 30 consists of two pieces of open-faced channels 32 and 33 welded together in T-formation, piece 32 serving as the stem, and piece 33 as the cross-bar. A number of horizontally elongated holes 34 are formed in cross-bar 33, and a pair of vertically elongated holes 35 in stem 32. The stem is bolted between a pair of column channels, and cross-piece 33 is bolted between the bottom rail channels when the junction spacer is used at the bottom. When a spacer 30 is used at the top it is turned upside down and cross-bar 33 is bolted between the top rail channels. In all cases, the elongated holes provide for adjustment of the spacer to the exact position desired.

A corner spacer 31 consists of two pieces of open-faced channels 36 and 37 welded together to form the legs of an angle. Leg 36 has a pair of vertically elongated holes 38 and leg 37 has a pair of horizontally elongated holes 39.

To assemble the partition, the bottom rail channels are bolted to the floor of the building by bolts 29, in the desired location, with the requisite number of corner spacers 31 and junction spacers 30 bolted between the channels at the appropriate points. The end rail channels are then secured with the requisite number of spacers 18 in place, to supports in the building. For example, in the case of a wall to wall partition the end rails are bolted to opposite walls. In other types of layouts the end rails may be bolted to a post, door jamb, or other suitable support. The intermediate column assemblies are then assembled and secured to the bottom junction spacers. If the partition extends to the ceiling, the top rail channels are bolted to the ceiling and fastened to the column assemblies and end rails by junction spacers and corner spacers, respectively. In the case of a low partition, a cap strip may be bolted to the top of the top rail.

When the members of the framework have all been assembled together, the panels 15 are placed in the openings of the framework and secured by means of the retainer strips which are pressed on to the framework channels.

The entire partition may be readily dismantled by removing the retainer strips and panels and unbolting the framework members. The partition can then be moved and reassembled at another location. If, for any reason, panels of thicker or thinner material than those originally installed are desired, only the spacers need be changed. The rest of the framework is re-usable. The adjustable thickness feature also permits standardization in manufacture of the frame channels.

What is claimed is:

1. A structural partition comprising: a supporting frame, including horizontal rails, a pair of upright end rails and an intermediate column assembly defining together a pair of generally rectangular openings, said column assembly and horizontal rails each comprising a pair of channels disposed back to back; a pair of T-shaped spacers each having a stem removably secured between

the channels of said intermediate column, and a cross-piece removably secured between the channels of one of said horizontal rails; a pair of panels, one mounted in each of said openings and each having a side margin abutting the channels of said intermediate column; and a pair of securing strips removably secured to the channels of said intermediate column and each having side flanges overlapping one of said margins.

2. A structural partition comprising: a supporting frame including horizontal rails and a pair of upright column assemblies, defining a generally rectangular opening, each of said column assemblies comprising a pair of channels disposed back to back and having open sides facing outward and spacers removably secured between said channels; a panel disposed in said opening and having side

5 margins abutting said channels; and securing strips covering the open sides of said channels, each strip having spring flanges engaged in the respective channel and a side flange overlapping one of said side margins, said horizontal rails comprising channels disposed back to back and having open sides facing outward, and having four angle-shaped spacers each having one leg secured between the channels of one of said horizontal rails and another leg secured between the channels of one of said column assemblies.
